UNITED STATES PATENT OFFICE

ARTHUR S. HUBBARD, OF QUINCY, MASSACHUSETTS, ASSIGNOR, BY MESNE ASSIGNMENTS TO THE TURNER TANNING MACHINERY COMPANY, OF PEABODY, MASSACHUSETTS, A CORPORATION OF MAINE

MANUFACTURE OF PATENT LEATHER

Application filed July 18, 1923, Serial No. 652,259. Renewed May 8, 1928.

This invention relates to the making of varnish coats on articles of manufacture and is herein described with reference to the curing or drying of varnished surfaces on pieces of leather.

In the manufacture of patent leather, according to methods heretofore practiced, prepared pieces of leather are coated with a varnish preparation in two or more coats, the succeeding coat in each case being applied after the preceding coat has been properly dried, usually by baking in an oven at 125° F. Even though the baking of the last or finish coat is continued for a period of fourteen hours or more at a temperature of approximately 140° F., the coat remains relatively soft and tacky. To cure or dry this tacky surface the pieces of leather are exposed out in the open to the direct rays of the sun for periods varying from seven to ten hours in accordance with the prevailing atmospheric conditions. At the end of this time the surface is dried or cured, as evidenced by the disappearance of the tackiness. Preferably a grassy plot is used for this solarizing operation both to minimize dust in the superadjacent air and to furnish moisture to the leather undergoing treatment so that it does not become desiccated. The necessity for the solarizing operation resides in the fact that varnished pieces of leather may neither be stored in contact with each other nor put to any practical use until the tackiness has been removed. Solarizing in the open air requires that the leather while stretched on frames should be carried out into open places and then returned under cover at the end of a solarizing period or at any time that threatening weather conditions arise. It occasionally happens that leather exposed in an open space for solarizing is damaged by a sudden shower of rain. The loss in such an accident is very considerable, since the surface must be subjected to rubbing with pumice to reduce the thickness of the coat, after which a fresh coat must be applied and the baking and solarizing repeated. It not infrequently happens in the event of long continued rainy weather that operations in the manufacturing of patent leather must be discontinued, particularly if the storage space within the plant is lim-

ited. Again, the amount and intensity of sunlight reaching the earth's surface varies from day to day throughout the year and, further, solar radiation in the ultra-violet region is found to vary at the earth's surface in accordance with elevation and with varying atmospheric conditions as determined, for instance, by atmospheric dust and humidity. Since ultra-violet radiation is a most important agent in the curing or drying operations on varnished surfaces, it follows that there is the greatest difficulty in securing uniformity in the desired results because of the described daily variation in the effectiveness of the curing or drying agent.

Accordingly, it is an object of this invention to provide for the curing or drying of varnished surfaces by artificial means which may be controlled to secure uniform results, independently of weather conditions, and in a fraction of the time heretofore consumed in the solarizing of patent leather.

To this end, and in accordance with important characteristics of the invention, curing or drying of varnished surfaces is secured by subjecting them to treatment by ultra-violet radiation from an artificial source. This is accomplished in the illustrated apparatus by exposing the varnished surfaces to treatment at close range by a bank or battery of fused quartz mercury arc lamps. In subjecting varnished surfaces to ultra-violet radiation at close range, there is secured the very great advantage of definite results in periods of time measured in minutes instead of in hours as heretofore in connection with solarizing operations. In practice it has been found advantageous to arrange the varnished surface at a distance of about eight inches from the lamps, in which case five to seven minutes' treatment is sufficient to produce the desired curing or drying of the varnished surface. It will be readily understood that the time of treatment may be varied by changing the spacing of the work with respect to the lamps, and that this spacing may be varied from five to fourteen inches with excellent results and the distance may even be reduced to two inches when

other factors are properly adjusted, as will be hereinafter described.

In an arrangement wherein pieces of leather are subjected to radiation from lamps at close range, it is particularly important that there should be relative movement of the lamps and of the varnished surfaces to secure greater uniformity of radiation over all parts of the varnished surfaces. Accordingly, conveyor means is provided in the illustrated construction for moving pieces of varnished leather past the bank of lamps and in close proximity thereto subject the varnished surfaces in a more nearly uniform manner to ultra-violet radiation for from five to twenty-five minutes, according to the nature of the varnish and the condition of the air in the treating chamber.

In thus speeding up the treatment of the varnished surfaces of pieces of leather by exposing them closely adjacent to the source of ultra-violet radiation, there is danger of damaging the leather through the heat absorbed by it while subjected to the intense radiation of the lamps at close range. Hence provision is made for regulating the temperature and moisture of the air in the treating chamber or enclosure to prevent burning of the leather and to secure atmospheric moisture adequate to prevent undue desiccation of the leather, thus simulating the conditions of solarizing in the open field. It is an important feature of this invention that means is provided for conditioning the air both as to temperature and moisture content and introducing the air thus conditioned into the treating chamber or enclosure to circulate therethrough. In the construction shown the means just referred to comprises a chamber within which the air may be suitably humidified and heated in accordance with the judgment of the operator. This air-conditioning chamber is located closely adjacent to the treating chamber so as to facilitate introduction of the conditioned air into the treating chamber without its suffering any change or modification of temperature or humidity. Conveniently, the treating chamber or enclosure is provided with an exit opening at a distance away from the inlet opening through which the conditioned air is introduced. As shown, means comprising a blower is interposed between the treating chamber and the air-conditioning chamber to cause transfer of the conditioned air from one chamber to the other and to cause a constant circulation of the conditioned air through the latter chamber. In order that the air within the treating chamber or enclosure may be suddenly changed if conditions should unexpectedly arise which cannot be met by the normal operation of the air-conditioning means, means is provided for drawing outside air,

that is, air of the prevailing temperature and humidity, into the treating chamber by the same blower which ordinarily discharges only conditioned air into the treating chamber.

During the treatment of the varnished hides for the drying of the varnish, nitrogen in the treating chamber or enclosure is caused to combine with other elements such as oxygen and as a part of my apparatus I use, when desired, a fixed nitrogen recovery apparatus. I blow a continuous stream of fresh or conditioned air through the chamber or enclosure and carry the exhaust air from the chamber, and when desired into apparatus for the recovery of the fixed nitrogen.

In the drawings, Fig. 1 shows diagrammatically an arrangement of a varnish treating chamber or enclosure in connection with an air humidifier and conditioner and with a nitrogen recovery apparatus;

Fig. 2 is a section taken at 2-2 in Fig. 3 and shows in elevation a schematic arrangement of quartz lamps in the treating chamber or enclosure;

Fig. 3 is an end elevation of a schematic arrangement of the treating chamber;

Fig. 4 is an end view of parts of the treating chamber or enclosure showing details of the hide holding frame and frame carrying means; and

Fig. 5 is an elevational view of a section of the inside of the treating chamber or enclosure showing details of a hide holding frame and frame carrying means.

As shown in the drawings there is provided a treating chamber or enclosure 1 along the middle of which is arranged a bank of fused quartz mercury arc lamps 2 which, as shown in Fig. 2, are spaced from each other a distance not greater than twice the major dimension of the lamps and which, in order to promote uniform distribution of the light therefrom, are arranged in a staggered formation. The bank of lamps extends substantially the whole length of the chamber 1.

During the curing or drying of the varnished surfaces the hides 4 are stretched on frames 3 in the manner shown in Fig. 5. These frames 3 are carried by the endless chain conveyors 5 along in a plane in close proximity to the lamp bank. It will be understood that the hides are exposed at close range to the lamps, that is, at distances between five and fourteen inches therefrom as conditions may determine. There are two of these conveyors 5, one on either side of the lamp bank as shown in Fig. 3. Figs. 4 and 5 show the form of these conveyors and their relation with respect to the lamp bank. The guide rails 7 and 9 serve to space the frames and hides a short distance from, i. e., closely juxtaposed to, the lamp supports and the guide rails 6 and 8 serve to keep the frames in place as they pass along with the conveyor

5. The rolls 11 support the conveyor and are close enough together to keep the conveyor from sagging under the weight of the frames. The rolls 10 also serve to guide the frames. 5 On the conveyor chain are links 17, suitably spaced, having engaging nubs 18 for imparting forward movement to the frame.

On the uprights 12 are hung the removable shelves 13 on each of which is supported a fused quartz mercury arc lamp 2 (as shown in the first vertical row of lamps in Fig. 2 of the drawing), the standards 14 supporting and spacing the lamps from the shelves. The frame uprights 12 and the shelves 13 serve to shield the lamps 2 from air currents such as might unduly affect the operating characteristics of the lamps. Suitable electrical connections are made to the leads 15 and 16 of the lamps. In one form of the apparatus of my invention I mount terminals 15a for the leads 15 and 16 on the shelves 13 and provide on the uprights 12 receiving terminals therefor (not shown) which are engaged thereby or disengaged therefrom on the placing of the shelf on its support or upon removing it therefrom, respectively.

During treatment of the varnished hides, a blower 20 operates to blow, through the chamber 1, air which has been conditioned in an air conditioner 19 provided with an electrical heating device 21 controlled by a manually operable switch 23 so that the air may be heated in accordance with the judgment of the operator. In this same chamber 19 the air may be humidified to the desired extent by a well-known form of humidifier (not shown). If conditions in the treating chamber or enclosure 1 should at any time require a sudden change in the temperature 40 and humidity of the air therein, a valve 24 in a pipe 26 may be opened so that air of the prevailing temperature and humidity may be drawn in from the outside to modify immediately the conditioned air within the chamber 1. When pipe 26 is open, the chamber 19 may be partially or wholly closed off by operation of a valve 27. Conveniently a blower is provided at 30 to assist in transferring the air from chamber 1 to a nitrogen-fixation chamber 28, the air subsequently passing out of chamber 28 through a suitable outlet (not shown). The pipe leading to blower 30 may be shut off and a second pipe 32, without a blower, may be utilized as the connection between chambers 1 and 28.

The operation of the apparatus of my invention is as follows: Hides 4 are stretched in frames 3 and varnish applied thereto. After the varnish vehicle or solvent has been 60 evaporated, as by heating in an oven, the frames are placed in the slideways which are on each side of the lamp bank where they are carried along the lamp bank by the conveyor chain 5. During the exposure the lamps are 65 suitably energized and there is blown,

through the chamber by means of the blower 20, air which has been conditioned in conditioner 19 (see Fig. 1). The conveyor chain 5 is actuated at a speed to carry the hides through the chamber and to expose them to 70 the influence of the ultra-violet light for from five to twenty-five minutes according to the nature of the varnish and the condition and nature of the air in the chamber 1. At these speeds, in my apparatus and by my method, 75 the varnish of the hides or other articles, removed from the chamber at the end of the given time, is dry and the hides or other articles are ready for shipment or use.

During the drying of the varnish by the 80 ultra-violet radiation of the fused quartz mercury vapor arc lamps, an appreciable amount of nitrogen is fixed. The exhaust air from chamber 1 is led through suitable apparatus 85 28 for recovering this fixed nitrogen from the air (see Fig. 1) to save it for use in the arts generally.

Heretofore varnish treating has been accomplished with the light source mounted a 90 considerable distance away from the varnished surface. It seems to me that reactions have thus been set up in the light field between the surface and the source which cut down the efficiency of the process and apparatus. By the use of my new process and 95 apparatus it will be observed that the varnished surface is brought within the area of all the rays emitted by the light source and preferably in close proximity thereto with the result that maximum drying and fixing 100 efficiencies are obtained, and any deleterious reactions which take place in the apparatus, of necessity, take place in the chamber at a point remote from the varnished surface.

I claim as my invention:

1. In a varnish drying apparatus, in combination, a bank of fused quartz mercury arc lamps, frames carrying varnished fabrics or hides, a conveyor and slideways for said frames along each side of said lamp bank and in close proximity thereto, whereby said frames and hides are carried past said lamps, an enclosure for said lamp bank, slideways, conveyors and frames, an air conditioner and humidifier, means for circulating air from the conditioner and humidifier through the enclosure, the enclosure being provided with an exhaust vent, and electric supply mains for said mercury arc lamps.

2. In apparatus for drying varnished fabrics or hides, in combination, a row of upright supports, removable shelves mounted on said supports in vertically and horizontally staggered relation, fused quartz mercury arc lamps mounted on said shelves, electric supply leads for said lamps, hide or fabric stretching frames, conveyors for said frames, one on each side of said row of uprights and lamp bank carried thereby in close proximity to said lamp bank, slideways for said frames,

- and an enclosure for the above said apparatus, an air conditioning chamber connected to said enclosure, means for propelling air from said chamber to said enclosure, said enclosure being provided with an exhaust vent, and means for shutting off the connection between said chamber and enclosure, and for admitting outside air through said propelling means to said enclosure.
10. The process of passing freshly varnished articles and humidified air to exposure to light rich in ultra-violet rays, whereby the varnish is dried and nitrogen from the air is fixed, carrying said articles from such exposure, and passing the air on to recovery apparatus, and saving the fixed nitrogen therein.
11. In an apparatus for drying varnished surfaces of articles of manufacture, a treating chamber, a bank or battery of lamps serving as the source of ultra-violet radiation, and means for supporting the articles to be treated at a distance of approximately five inches from the lamps.
12. That improvement in methods of treating varnished surfaces of articles of manufacture which comprises subjecting the varnished surfaces of the articles to treatment by a bank of lamps uniformly spaced with respect to each other and serving as a source of ultra-violet radiation, and, during treatment by radiation, moving the varnished articles continuously past the bank of lamps at a uniform distance therefrom and at a predetermined speed to secure uniformity in the treatment of the varnished surfaces.
13. That improvement in methods of treating varnished surfaces of articles of manufacture which comprises subjecting the varnished surfaces of the articles to treatment by a bank of lamps arranged in a plane in uniformly spaced relation with respect to each other, the lamps serving as a source of ultra-violet radiation, and, during treatment by radiation, moving the varnished articles continuously past the bank of lamps in a path parallel to the plane thereof and at a predetermined speed to secure uniformity in the treatment of the varnished surfaces.
14. That improvement in methods of treating varnished surfaces of articles of manufacture which comprises subjecting the varnished surfaces of the articles to treatment by a bank of lamps serving as a source of ultra-violet radiation at close range, approximately five inches from the bank of lamps, and, during treatment by ultra-violet radiation, moving the varnished articles past the bank of lamps at a predetermined speed to secure uniformity in the treatment of the varnished surfaces.
15. That improvement in methods of treating varnished surfaces of articles of manufacture, which comprises subjecting the varnished surfaces of the articles to ultra-violet radiation from a bank of lamps at a uniform distance therefrom and, during treatment by radiation, moving the varnished articles past the bank of lamps at a predetermined speed in approximately five minutes.
16. That improvement in methods of treating varnished surfaces of articles of manufacture which comprises subjecting the varnished surfaces of the articles to ultra-violet radiation from a bank of lamps at a uniform distance of approximately five inches and,

10 during the treatment, moving the varnished articles past the bank of lamps at a predetermined speed in approximately five minutes.

15 Signed at Hoboken, in the county of Hudson and State of New Jersey, this 17th day of July, A. D. 1923.

ARTHUR S. HUBBARD.
